(57) CLAIM

The ornamental design for a loveseat, as shown and described.

DESCRIPTION

FIG. 1 is a front and right perspective view of the loveseat showing my new design.

FIG. 2 is a front view of the loveseat.

FIG. 3 is a rear view of the loveseat.

FIG. 4 is a left side view of the loveseat.

FIG. 5 is a right side view of the loveseat.

FIG. 6 is a top view of the loveseat; and,

FIG. 7 is a bottom view of the loveseat.

Any shading and cross-hatching are not features of the design but are utilized to illustrate the surface contours of the loveseat design in the drawings.

The broken lines illustrate portions of the loveseat that form no part of the claimed design.
